DESIGN FOR A JEWELRY SETTING OR SIMILAR ARTICLE

Henry R. Kiepe, Newark, N. J., assignor to Baker & Company, Inc., Newark, N. J., a corporation of New Jersey

Application October 12, 1939, Serial No. 87,643

Term of patent 14 years

To all whom it may concern:

Be it known that I, Henry R. Kiepe, a citizen of the United States and a resident of Newark, in the county of Essex and State of New Jersey, have invented a new, original, and ornamental Design for Jewelry Setting or Similar Article, of which the following is a specification, reference being had to the accompanying drawing, forming part thereof.

scale of a jewelry setting showing my new design.

Figures 3 and 4 are transverse vertical sectional views taken on the lines 3-3 and 4-4, respectively, of Figure 1.

I claim:

The ornamental design for jewelry setting or similar article, as shown.

HENRY R. KIEPE.
